TELEPHONE SYSTEM

**Kenneth L. Frederick, Berwyn, Ill., assignor to
Western Electric Company, Incorporated, New
York, N. Y., a corporation of New York**

Application June 30, 1942, Serial No. 449,083

7 Claims. (Cl. 179—22)

This invention relates to telephone systems and particularly to automatic telephone systems in which connections are established by means of crossbar switches.

An object is to simplify automatic telephone systems of this kind in which a small number of subscribers' lines are involved, such as private branch exchange systems.

Heretofore such systems have been arranged in which single crossbar switches served both as line finders and as connectors, that is, a connection between a calling subscriber and a called subscriber may be made by the establishing of a connection through a line finder section from the calling line to one end of a link, and when the calling subscriber dials the number of the called subscriber, the connector section operates to complete a connection from the other end of this link to the called line.

The applicant's invention has been applied to a system of this kind and relates particularly to the line-finder section of the system. The special arrangement in which the features of the applicant's invention appear is such that trunks or outgoing links from the line-finder section are arranged in pairs on the horizontals while incoming links are arranged in pairs on the verticals in the line-finder crossbar switches. Each outgoing link in each pair has access to a corresponding incoming link in each pair and each subscriber's line has access to a separate pair of said incoming links. These incoming links, of course, also appear in the connector section of the crossbar switches. The general arrangement of the system to which the connection has been applied is such that the calling subscriber will establish a connection through an incoming link to an outgoing link in the line-finder section, and this outgoing link extends through other selector switches and mechanisms through which a connection is established to a trunk terminating in the connector section where a connection is established from this trunk through one of the pair of vertical incoming links to a called subscriber's line.

A feature of the invention resides in a busy test control arrangement for establishing a connection between a calling line and one of the idle outgoing links over a vertical incoming link and the arrangement is such that when a subscriber calls a first pair of outgoing links are chosen of which one at least is idle and the first idle link of this pair is then chosen for connection to the subscriber over a corresponding vertical link, that is, the idle link determines which ver-

tical link shall be used and the pair of links of which this idle link is one determines which cross-connection shall be used to connect the idle link to the corresponding vertical link.

5 The arrangement has been illustrated in the accompanying drawings, in which:

Fig. 1 shows in general and in diagrammatic form a switching plan of a private branch exchange system in which the applicant's invention has been incorporated;

10 Figs. 2, 3 and 4 arranged in accordance with Fig. 5 illustrate in general the trunking and linking arrangement for an exchange of a capacity of 100 lines, and Figs. 6 and 7 arranged with Fig. 6 above Fig. 7, show a section of a line-finder connector switch in which one subscriber's line terminates and the associated circuits and mechanism embodying the applicant's invention.

15 Referring now to the drawings, and particularly to Fig. 1, the private branch exchange illustrated may consist of, in general, a group of line-finder and connector switches shown at 1 in which 90 subscribers' lines indicated at 2 and ten trunks indicated at 3 may terminate and from

20 the line-finder sections, outgoing links, such as 4, may extend to a selector switch 5, back to an incoming trunk arrangement 6 to the connector sections of the switches 1. When a subscriber or trunk in group 2 or 3 calls, an outgoing link

25 in the line-finder section of the group 4 is chosen and the connection is extended through this line-finder section to the selector 5. The calling subscriber or trunk may then dial two digits. The first digit will operate the selector switch to find

30 a trunk in the group 6 that extends to a particular group of subscribers' lines in which the called subscriber's line is one, then a second digit is dialed and the chosen trunk is then connected to the called subscriber's line. This may be accomplished in any well-known manner through registers and other mechanisms well known in the art for selecting links and trunks through crossbar switches and need not be illustrated or described in detail as the applicant's invention is

35 not concerned with the general plan. The only reason why this brief description is made of the system is to clearly place the applicant's invention in the art.

40 If this hundred-line capacity exchange is considered, the general wiring plan has been outlined in Figs. 2, 3 and 4. It is understood that the various circuits are here merely represented by single conductors and the contacts at the cross-points of the switches are merely represented by 45 a single contact for the sake of simplicity and

clearness. Considering the line-finder connectors, these switches may be divided in five units with the connector sections marked 10 to 14 and with the line-finder sections marked 15 to 19. Each unit serves a group of twenty subscribers' lines, the lines being marked lines 1 to 20, 21, 40, 41 to 60, 61 to 80, and 81 to 100, respectively, in the five units. In each group of twenty lines, each line has access to a separate pair of vertical incoming links such as 20 and 21 in the connector section 10 for line 1. Each of the vertical links of each twenty pairs in a line-finder section has access at three crosspoints to any one of three separate outgoing links. That is, the left-hand vertical links of each pair of the twenty pairs in the first line-finder section 15 have access to links 22, 23 and 24 and the companion links have access to the three links 25, 26 and 27. This will provide, therefore, for the five units, a group of thirty links outgoing from the line-finder sections 15 to 19. By these means, therefore, any one of the twenty subscribers in any group has access to six outgoing links by first establishing a connection to one or the other of the vertical links to choose a group of three links, and connect this vertical link to one of the three chosen links. These thirty outgoing links are then connected at 30 to two groups of five trunks each in any suitable cross-connecting manner so that, for example, the fifteen odd-numbered links are cross-connected with three links to one of the five trunks in the group and the fifteen even links are cross-connected with three links to one of the trunks in the other group. These ten trunks are then connected to appear in ten verticals in ten succeeding sections of the selector switch 32. For example, in section 33 the trunk 34 is connected to the vertical link 35. Each vertical link in the tens section has access to five outgoing trunks at ten crosspoints, for example, link 35 has access to five trunks 36, thus fifty trunks extend from the selector 32 to the connector sections 10 to 14 of the line-finder connector. These fifty outgoing trunks are then divided in groups of ten, each group appearing in a separate level in the connector sections so that these connector sections are provided for that purpose with five levels of contacts, that is, a pair of incoming trunks one from each of two adjacent groups of five has access to twenty subscribers' lines in a corresponding level with one trunk of a pair having access to one of each pair of vertical links and the other having access to the other one of each pair of vertical links in the group of forty having access to twenty subscribers' lines. For example, the outgoing trunk 38 of group 36 has access to vertical link 20 of line 1 and the corresponding vertical links of the other nineteen subscribers' lines in section 10, while link 40 of group 41 has access to vertical link 21 of line 1 and the corresponding vertical links of the other nineteen subscribers' lines in section 10. Thus, the groups of links 36 and 41 have access to the first level of sections 10 to 14 and correspondingly the other groups of trunks have access to the other four levels.

In general, therefore, if a connection is desired by the subscriber of line 1 to the subscriber of line 20, the operation would be as follows. The subscriber of line 1 in seizing his line causes operations to take place as will be described in detail hereinafter to establish a connection to an idle outgoing link of the six links 22 to 27 in the line-finder section 15 by first determining whether there is an idle link available in the 75

first pair of links 22 and 25 or if the first pair is busy in the second pair 23 and 24 and if the second pair is busy in the third pair 24 and 27. Thus the first pair in which a link is idle will then be preselected. It is then determined whether a first or a second link in the chosen pair is idle, that is, for example, if the first pair 22 and 25 has been preselected, and the link 22 is idle, connection would be established to this link over a corresponding vertical link 20, the vertical link 20 being also chosen at that time to establish a connection to the subscriber 1 at contacts 45 which will be closed due to the fact that the vertical link 20 was chosen. These selecting operations are performed in accordance with applicant's invention which will be described in detail in connection with Figs. 6 and 7 hereinafter. For the present the connection from this chosen link to the subscriber's line 20 will be described in general. Consider then that after the link 22 has been chosen, it would follow that this link will be connected over the link 34 to the verticals 35 in Fig. 33 of the selector 32. The subscriber will now dial two digits, for example, 2 and 0. Digit 2 will operate the selector 32 to establish a connection at the crosspoint 46 between vertical 35 and trunk 38 in section 33. This, of course, determines that a subscriber in the first group of twenty is desired as link 38 has access to this group and also the choice of link 38 determines that a left-hand vertical link in the connector section 10 shall be used by the operation of contacts 41. Now all that remains is to dial digit 1. This causes the connector section 10 to be operated to establish a connection between link 38 at crosspoint 49 with the subscriber's line 20 through the connection at 47.

All of these operations in the selector switch 32 and the connector section 10 do not form part 40 of the applicant's invention so that further detailed descriptions appear to be unnecessary. On the other hand, the part of this switching system to which applicant's arrangement has been applied will now be described in detail in connection with Figs. 6 and 7 where one subscriber's line has been shown with the necessary detail circuits for the establishing of connections from this line to one of the six links to which it has access in the line-finder section. It should be noted that the subscriber's line 1 is incoming to the connector section 10 and terminates in the two vertical links 20 and 21 and may be connected through contacts at the crosspoint 45 to link 20 by the operation of the primary select magnet 50 or through contacts at the crosspoint 51 to link 21 by the operation of the primary select magnet 52 followed in either case by the operation of the usual hold magnet 53. The hold magnet 53 serves, of course, also for connecting either one of these two links to one of the six outgoing links 22 to 27 through three groups of contacts at the crosspoints 55, 56 and 57. The select magnets for these three crosspoints are marked 58, 59 and 60, respectively, in the line-finder section 15. The hold magnet 53 also serves for connecting any one of the ten trunks incoming to a connector section 10 from the selector 32 with the aid, of course, of the select magnets 62, 63, 64, 65 or 66 to establish connections at the crosspoints 67, 68, 69, 70 or 71 in the general manner as described hereinbefore.

If it is assumed then that the subscriber of line 1 calls, the establishing of this connection causes the operation of relay 80 from battery, a winding of relay 80 through contacts of relay 81

over the tip and ring conductors through the calling subscriber's loop, contacts of relay 81, another winding of relay 80, to ground at contacts of relay 83. Relay 80 in operating provides a locking circuit for itself through its right-hand armature and front contact to ground, independent of the ground supplied at contacts of relay 83 and closes an obvious circuit for the operation of relay 83. An idle outgoing link will now be selected. As hereinbefore stated, it will first be determined whether a link is idle in the first group of two, that is, links 22 and 25 controlled by contacts at the crosspoint 55 or in the second group of two, that is, links 23 and 26 controlled by contacts at crosspoint 56 or in the third group of two, that is, links 24 and 27 controlled by the contacts at the crosspoint 57. If one of the links in the first group is idle, for example, link 22, it will be noted that the link-busy relay 90 for this link is not operated. Consequently, on the operation of relay 83 a circuit is completed for the operation of the select magnet 58 which controls the contacts at the crosspoint 55. This circuit may be traced from battery through contacts of relay 83, contacts of select magnets 62 to 66 in the connector section, contacts of busy relay 90, winding of select magnet 58 to ground. Another circuit is simultaneously closed for the operation of the vertical link select magnet 50 from battery, contacts of relay 83 and the select magnets as hereinbefore traced through contacts of relay 90, winding of select magnet 50 to ground. On the operation of the select magnet 58 a circuit will be closed for the hold magnet 53 from battery through the winding of this magnet, contacts of relay 80 and contacts of select magnet 58 to ground, thus causing a connection to be established at the crosspoint 55 from the subscriber's line 1 through contacts at the crosspoint 45 controlled by the select magnet 50, the vertical link 20, contacts at the crosspoint 55 to the conductors of link 22. A connection from ground will now be established from the sleeve lead of link 22, contacts at crosspoints 55 and 45, winding of the cut-off relay 81 to battery causing the operation of this relay which in operating closes an obvious locking circuit for the hold magnet 53 and opens the connections for relay 89 which release causing the release of relay 83, the select magnets 50 and 58. The busy relay 90 will now also operate from battery through the winding of this relay to the same ground over the sleeve lead of link 22 to hold this link busy. The fact, therefore, that the busy relay 90 was not operated when the call was made determines that the link 22 of the first pair 22 and 25 was idle. Had this relay been operated, and had the other link 25 of this pair been idle, the fact that the busy relay 90 for this link 25 was not operated, would have determined that the connection should be established to this link 25 instead. If this had been the case when relay 83 operated, the circuit traced from battery, contacts of relay 83 and the select magnets of the connector section 10 would have extended through contacts of the actuated busy relay 90, contacts of released busy relay 98 and winding of the same select magnet 58 and cause the operation of this magnet, but instead of select magnet 59 being operated at this time, the select magnet 52 would operate simultaneously with the select magnet 58 over the circuit from the battery at relay 83 through the contacts of the select magnets in the connector section 10.

operated contacts of relay 90, contacts of released relay 98, winding of select magnet 52 to ground. Consequently, when the select magnet 52 operates, the subscriber's line 1 will in this case be connected through contacts at crosspoint 51 controlled by the select magnet 52, link 21, contacts at crosspoint 55 to link 25. When this connection is made the busy relay 98 will operate from battery over the sleeve of link 25 to ground. Thus it will be seen that if either one or both of links 22 or 25 are idle, the connection would be extended over one or the other of these links, provided that if the first link 22 were idle, this link would be chosen for the connection, and if the link 25 only were idle, this link 25 would be used for the connection. If both links 22 and 25 are busy, both relays 90 and 98 will be operated and the choice of an idle trunk would be made in the second pair 23 and 26 and similarly a choice of a first idle one of this pair would be chosen for the connection. For example, if link 23 were idle, busy relay 103 will be in released condition. In this case as busy relays 90 and 98 are operated, the select magnet 59 will operate over the circuit at the contacts of relay 83 through the contacts of the select magnets in the connector section, contacts of operated busy relays 90 and 98 and contacts of busy relay 103, winding of select magnet 59 to ground. The select magnet 50 would also operate to choose the vertical link 20. On the other hand, if link 23 is busy and link 26 is idle, the select magnet 59 will operate as before but due to the fact that relay 103 is now operated, the select magnet 52 will operate instead of the select magnet 50 to extend the connections over link 21. Similarly, if the first four links are busy, an idle trunk of the pair 24 and 27 will be chosen and always a first idle link of the pair.

It is, therefore, seen that with the applicant's invention as applied to this kind of system, the idle outgoing links will be chosen in a certain order. That is, first it is determined whether there is an idle link in the first, second or third pair. If an idle trunk exists in the first pair it is determined whether a first or a second link in this chosen pair is idle. If the first link is busy the second link will be chosen. If both links in the first pair are busy, the first idle link in the next pair will be chosen, etc. This choice of an idle link is determined by the six busy link relays 90, 98, 103, 108, 109 and 110. Each one of these busy relays will also determine which vertical link is to be employed in establishing a connection through the line-finder section to the link chosen from the calling subscriber. That is, for example, relay 90 will determine that select magnet 50 will be operated to select vertical link 20 and relay 98 will determine that the select magnet 52 will be operated to choose vertical link 21, etc. This arrangement enables a pair of links to be terminated at a single crosspoint in each line-finder section and a common set of six link-busy relays may be employed for the establishing of connections for twenty subscribers with six links.

What is claimed is:

1. In a telephone system, a crossbar switch having intersecting horizontal and vertical rows 70 of contacts, pairs of trunks, each pair terminating in a separate horizontal row of contacts, pairs of links, each pair terminating in a separate vertical row of contacts, said horizontal and vertical rows of contacts at each intersecting point being arranged to establish a connection

between one trunk and one link of the two intersecting pairs over one set of said contacts and between the other trunk and the other link over another set of said contacts, subscribers' lines terminating in said switch, two separate sets of contacts in said switch for each subscriber's line for connecting it to one or the other of an associated pair of links, and means responsive to the seizure of a subscriber's line for choosing a first pair of trunks of which one at least is idle, for choosing a first trunk of said pair, if idle, and connecting said idle trunk to the associated link of the pair to which the calling line has access, over the contacts at the corresponding crosspoint, and connecting said link to the calling line over the corresponding separate set of contacts.

2. In a telephone system, a crossbar switch having intersecting horizontal and vertical rows of contacts, pairs of trunks, each pair terminating in a separate horizontal row of contacts, pairs of links, each pair terminating in a separate vertical row of contacts, a select magnet for each row of horizontal contacts, a hold magnet for each row of vertical contacts, means responsive to the actuation of any select magnet followed by the actuation of any hold magnet for establishing a connection between the associated pair of trunks and pair of links over the contacts at the intersection of the associated horizontal and vertical rows of contacts, subscribers' lines terminating in said switch, two separate sets of contacts for each subscriber's line for connecting it to one or the other of an associated pair of links, a select magnet for one set of contacts associated with each subscriber's line and one link in each pair, a select magnet for the other set of contacts associated with each subscriber's line and the other link in each pair, means responsive to the actuation of either of said last-mentioned two select magnets and any hold magnet for establishing a connection between the associated subscriber's line and the associated link over the corresponding set of contacts, means responsive to the seizure of a subscriber's line for actuating the select magnet for a first pair of trunks one of which at least is idle, for actuating the select magnet for the link having access to a first idle trunk of said first pair, and means responsive to the actuation of said select magnet for said first pair of trunks for actuating the hold magnet for the links associated with the calling subscriber's line for establishing a connection between said subscriber's line, said link and said idle trunk.

3. In a telephone system, a crossbar switch having contacts arranged in horizontal and vertical rows and select magnets and hold magnets for establishing connections between contacts and intersecting rows, outgoing trunks terminating in pairs in contacts of individual horizontal rows, incoming trunks terminating in pairs in contacts of individual horizontal rows, links terminating in pairs in contacts of individual vertical rows, subscribers' lines each terminating in one set of contacts in one horizontal level in position to connect with the contacts of one link of a pair and terminating in another set of contacts in another horizontal level in position to connect with the contacts of the other link of said pair, means responsive to the seizure of a subscriber's line for actuating two select magnets and one hold magnet for establishing a connection between said subscriber's line, one of the associated links and a first idle trunk of a first

pair in which at least one trunk is idle, and means for seizing a particular incoming trunk and actuating two select magnets and one hold magnet for establishing a connection between said incoming trunk, a particular link of the pair associated with a particular subscriber's line and connecting said link with said particular subscriber's line.

4. In a telephone system, a crossbar switch having contacts arranged in horizontal and vertical rows and select magnets and hold magnets for establishing connections between contacts at intersecting rows, trunks terminating in pairs in contacts of individual horizontal rows, links terminating in pairs in contacts of individual vertical rows, subscribers' lines each terminating in one set of contacts in one horizontal level in position to connect with the contacts of one link of a pair and terminating in another set of contacts in another horizontal level in position to connect with the contacts of the other link of said pair, and means responsive to the seizure of a subscriber's line for actuating two select magnets and one hold magnet for establishing a connection between said subscriber's line, one of the associated links and a first idle trunk of a first pair in which at least one trunk is idle.

5. In a telephone system, a plurality of crossbar switches, each having contacts arranged in horizontal and vertical rows and select magnets and hold magnets for establishing connections between contacts of intersecting rows, trunks terminating in pairs of contacts of individual horizontal rows in one or more of said crossbar switches, links individual to each crossbar switch terminating in pairs of contacts of individual vertical rows in said switch, subscribers' lines individual to each crossbar switch, each subscriber's line terminating in one set of contacts in one horizontal level in position to connect with the contacts of one link of a pair and terminating in another set of contacts in another horizontal level in position to connect with the contacts of the other link of said pair, means responsive to the seizure of a subscriber's line in any switch for actuating two select magnets and one hold magnet for establishing a connection between said subscriber's line, one of the associated links and a first idle trunk of a first pair in which at least one trunk is idle.

6. In a telephone system, a crossbar switch having contacts arranged in horizontal and vertical rows and select magnets and hold magnets for establishing connections between contacts of intersecting rows, trunks terminating in pairs in contacts of individual horizontal rows, links terminating in pairs in contacts of individual vertical rows, subscribers' lines each terminating in one set of contacts in one horizontal level in position to connect with the contacts of one link of a pair and terminating in another set of contacts in another horizontal level in position to connect the contacts of the other link of said pair, means responsive to the seizure of a subscriber's line for choosing and actuating the select magnet for a first pair of trunks of which one at least is idle and for simultaneously choosing and actuating the select magnet for the link having access to the first idle trunk of said first pair and for actuating the hold magnet for the links associated with the calling subscriber's line for establishing a connection from said calling subscriber's line over the chosen link and said chosen idle trunk.

7. In a telephone system, a crossbar switch having contacts arranged in horizontal and vertical rows and select magnets and hold magnets for establishing connections between contacts at intersecting rows, trunks terminating in pairs in contacts of individual horizontal rows, links terminating in pairs in contacts of individual vertical rows, subscribers' lines each terminating in one set of contacts in one horizontal level in position to connect with the contacts of one link of a pair and terminating in another set of contacts and another horizontal level in position to connect with the contacts of the other link of said pair, means including a busy test relay for each trunk responsive to the seizure of a subscriber's line for choosing and actuating the

select magnet for a first pair of trunks of which one at least is idle as determined by the idle condition of the associated busy test relay and for simultaneously choosing and actuating the select magnet for the link having access to the first idle trunk of said first pair as determined by the idle condition of said associated busy test relay and for then actuating in response to the operation of said first select magnet the hold magnet for the links associated with the calling subscriber's line, and means responsive to the operation of said select magnets and hold magnets for establishing a connection from said calling subscriber's line over the chosen link and over the chosen idle trunk.

KENNETH L. FREDERICK.
